(57) **CLAIM**

The ornamental design for a tub spout, as shown and described.

DESCRIPTION

FIG. 1 is a top rear perspective view of the tub spout showing my new design;

FIG. 2 is a top front perspective view thereof;

FIG. 3 is a left side elevational view thereof, the right side being a mirror image;

FIG. 4 is a top plan view thereof;

FIG. 5 is a bottom plan view thereof;

FIG. 6 is a rear elevational view thereof; and,

FIG. 7 is a front elevational view thereof.

The broken line showing of the diverter valve handle and spout tip in FIGS. 1 and 2, of the spout base in FIG. 2, and of the diverter valve handle aperture in FIG. 4 are for purposes of illustration only and forms no part of the claimed design.
